UNITED STATES PATENT OFFICE.

JULES H. VENON, OF NEW YORK, N. Y.

DESIGN FOR A DISH.

Application filed October 31, 1922. Serial No. 4,174. Term of patent 7 years.

To all whom it may concern:

Be it known that I, JULES H. VENON, a citizen of the United States, and resident of the city, county, and State of New York, have invented a new, original, and ornamental Design for Dishes, of which the following is a specification, reference being had to the accompanying drawings, forming part thereof.

Fig. 1 is a side elevation and Fig. 2 is a plan view showing my new design for a dish.

I claim:—

The ornamental design for a dish as shown.

J. H. VENON.
